BY Edgar T. Co.

ATTORNEYS

UNITED STATES PATENT OFFICE.

CHARLES I. WETSELL, OF BROOKLYN, NEW YORK.

BOOT-BLACK'S CABINET.

No. 895,705.

Specification of Letters Patent.

Patented Aug. 11, 1908.

Application filed February 29, 1908. Serial No. 418,463.

To all whom it may concern:

Be it known that I, CHARLES I. WETSELL, a citizen of the United States, and residing at Brooklyn, in the county of Kings and State 5 of New York, have invented certain new and useful Improvements in Boot-Blacks' Cabinets, of which the following is a specification, such as will enable those skilled in the art to which it appertains to make and use the 10 same.

This invention relates to boot-blacks' cabinets or boxes; and the object thereof is to provide an improved device of this class comprising a suitable box or case having a 15 hinged cover, and within which is placed a foot rest connected with the box or case and said cover and adapted to be raised above the box or case and supported thereover when the cover is opened, and to be lowered 20 into the box or case and concealed therein when the cover is closed.

The invention is fully disclosed in the following specification, of which the accompanying drawing forms a part, in which the 25 separate parts of my improvement are designated by suitable reference characters in each of the views, and in which;—

Figure 1 is a sectional side view of my improved boot-blacks' cabinet or box, and; 30 Fig. 2 a partial transverse section on the line 2—2 of Fig. 1.

In the practice of my invention, I provide a box or case *a* preferably provided with a bottom *a*², and preferably supported by legs 35 *a*³. The box or case *a* is provided with a cover *a*⁴ hinged at one side as shown at *a*⁵, and in practice I provide a foot rest *b* preferably composed of metal and of any desired form, and to the heel portion of which is pivoted or hinged a link member or plate *c*, the 40 pivotal connection of which with the foot rest *b* is shown at *c*², and said link member or plate *c* is pivoted or hinged at *c*³ to a plate *c*⁴ secured to the front of the box or case mid-45 way thereof.

When the heel portion of the foot rest *b* is in the position shown in full lines in Fig. 1, it rests on the link or plate member *c* and cannot descend lower than the position shown. 50 The top portion of the foot rest *b* is provided with a downwardly and backwardly directed arm *d*, the backwardly directed portion *d*² of which is provided with a slot *d*³, and the backwardly directed portion *d*² of the arm *d* 55 is hinged at *d*⁴ to a sleeve *e* vertically movable on a hanger *f* provided at its upper end

with a horizontal member *f*² rigidly secured to the bottom of the rear portion of the cover *a*⁴.

Mounted in the lower end portion of the 60 hanger *f*, and rotatable therein is a pin *g* provided with a transverse flat head *g*² adapted to pass through the slot *d*³ in the backwardly directed extension *d*² of the arm *d* when the cover *a*⁴ is raised and the foot rest *b* thrown 65 into the position shown in dotted lines in Fig. 1.

The operation will be readily understood from the foregoing description, when taken in connection with the accompanying draw- 70 ing and the following statement thereof.

In the position of the parts shown in full lines in Fig. 1, the cover *a*⁴ of the box or case *a* is closed and the foot rest *b* is inclosed in the said cabinet or box. If now the cover 75 *a*⁴ be raised into the position shown in dotted lines in Fig. 1 the foot rest *b* will be raised into the position also indicated in dotted lines in Fig. 1. In this operation the head *g*² of the rotatable pin *g* passes through 80 the slot *d*³ in the part *d*² of the arm *d*, and by turning said head transversely of said arm the foot rest *b* will be locked in the position shown in dotted lines, and will hold the cover *a*⁴ in a raised position, and said foot 85 rest will support in this position any pressure necessary to be put thereon.

When the operation of blackening a pair of boots or shoes is completed and it is desired to close the box or case the pin *g* is 90 turned by means of the head *g*² thereof till said head ranges parallel or in line with the slot *d*³ and the cover *a*⁴ may be lowered into the closed position, and in this operation the foot rest *b* will drop into the cabinet or box 95 as shown in full lines in Fig. 1.

My invention is not limited to any particular form of cabinet, box or case, all that is necessary being to provide a suitable device of this kind, and changes in, and modifications of the operative parts of my improvement as herein shown and described, may be made, within the scope of the appended claims, without departing from the spirit of my invention or sacrificing its advantages. 100

Having fully described my invention, what I claim as new and desire to secure by Letters Patent, is;—

1. A boot-blacks' cabinet or box, comprising a box or case provided with a hinged 110 cover, a foot rest, a plate hinged to the bottom of the heel portion of the foot rest and

at the front of the box or case, the toe portion of the foot rest being provided with a downwardly extending and backwardly directed arm, a hanger connected with the bottom of the rear portion of the cover, a sleeve movable on said hanger and to which said arm is hinged, the backwardly directed portion of said arm being provided with a longitudinal slot, and the bottom portion of said hanger with a rotatable pin the head of which is adapted to pass through said slot.

2. A boot-blacks' cabinet or box, comprising a box or case provided with a cover hinged at the back side thereof, a foot rest placed in said box or case and the heel portion of which is connected with the end portion of the box or case by a link or plate

member hinged beneath the heel portion of the foot rest and at the front of the box or case, a hanger connected with the rear portion of the cover, said foot rest being provided at its toe portion with a downwardly extending and backwardly directed arm, and a sleeve vertically movable on said hanger and to which said arm is hinged.

20

25

In testimony that I claim the foregoing as my invention I have signed my name in presence of the subscribing witnesses this 28th day of February 1908.

CHARLES I. WETSELL.
